UNITED STATES PATENT OFFICE.

FRANK G. BREYER AND EARL H. BUNCE, OF PALMERTON, PENNSYLVANIA, ASSIGNEES
TO THE NEW JERSEY ZINC COMPANY, OF NEW YORK, N. Y., A CORPORATION OF
NEW JERSEY.

BUILT-UP VERTICAL ZINC RETORT.

Application filed March 5, 1927. Serial No. 172,951.

This invention relates to externally heated vertical retorts or reducing chambers for smelting or reducing zinciferous materials, and has for its object the provision of an 5 improved retort or reducing chamber of this character.

At the present time, all commercial zinc reducing chambers or retorts (externally heated) are true monoliths, with but a single 10 opening for introducing the charge, withdrawing the residues and exiting the zinc-bearing gaseous products. This opening during the active reduction period is completely filled and closed from the atmosphere 15 by a condenser (and its luting) for the metallic zinc vapor. These monoliths are made by ramming plastic heat refractory or temperature resistant material into suitable molds or by extruding such material under pressure. The resulting plastic vessels 20 are most carefully dried and burned, and if the slightest crack appears are rejected as unfit to be placed in the heating chamber or laboratory of the zinc or spelter 25 furnace. The primary reason for making these retorts true monoliths and with but one opening is the full realization that the slightest leakage of heating gases into the retort is fatal to good condensation to zinc 30 metal of the zinc vapor evolved in the retort.

With small retorts of the size now commonly used in commercial spelter furnaces (6 to 9 inches internal diameter and about 4 to 5 feet long), the disadvantages of constructing the retorts as true monoliths are 35 not of particular importance. With reducing chambers of substantially greater capacity, such as contemplated in the improved method of zinc smelting described in our 40 copending patent application, Serial No. 163,902, filed January 27, 1927, the disadvantages of the true monolith construction become so great as to render this manner of making the reducing chamber commercially impracticable. Consequently, in the 45 construction of reducing chambers of relatively large reducing capacity "built-up structures" become a practical necessity. By "built-up structures" we mean structures 50 that are not molded, formed or cast as one piece from fluid or plastic base material, thereby forming a monolith, but on the contrary, are built up into the required size and shape by fitting together a number of pieces 55 or shapes of solid material which are bonded

together by some form of cement or joint filler. The zinc metallurgist, however, is not inclined to regard built-up reducing chambers with any favor, no doubt because of the many fruitless attempts to reduce 60 zinciferous material in built-up muffles. Even in the very early days of zinc smelting built-up muffles were proposed and tried, but these built-up structures invariably gave such poor recoveries of zinc and such poor 65 condensation to zinc metal that they were all abandoned in favor of the small truly monolithic retort that has become standard practice in zinc smelting for making zinc 70 metal.

In view of the use of built-up muffles in other industries and arts, it perhaps requires some explanation to understand why a built-up muffle has not heretofore proven satisfactory in the art of zinc smelting. In other industries, where built-up muffles are used under conditions of high temperature, small leaks into or out of the muffle are not of serious consequence. In the case of zinc smelting in the reducing chambers or retorts of the prior 75 art, however, the smallest leak into the reducing chamber or muffle has proven fatal to the good condensation of the zinc vapor evolved. This seems to be true even when there is some slightly greater pressure inside of the muffle than outside, since diffusion of oxygen into the muffle against the pressure therein appears to be of sufficient magnitude to bring about the harmful effect. In the early attempts to use built-up muffles 80 for zinc smelting, other difficulties were encountered due to slagging out or breaking of the bonds or joints, thereby causing cracks when the muffle-cleaning tools were used.

The principal difficulty, however, in the 85 former attempts to use built-up muffles in zinc smelting was due to the fact that the muffles were invariably tied in, supported by or their arches sprung from the furnace or laboratory lining in numerous places. 90 With the temperature of the muffle walls going from blackness when a fresh charge was put into the muffle up to 1200 to 1400° C., and often higher, before the last of the charge was worked-off, and these temperature changes repeated with every charge, the wall of the muffle contracted and expanded differentially with respect to the laboratory or furnace walls to which it was tied in and ruptures and cracks on the muffle 105 110

inevitably took place in consequence thereof.

We have discovered that if the muffle or retort is built up so that it is supported and tied in to the laboratory or furnace lining at only one place (preferably its base) and due regard taken of other factors, a built-up retort can be made sufficiently tight for good condensation of the zinc vapor evolved. We have further found that not only is it important that the reducing chamber or retort be not tied in at any other place than at its base, but that the shape of the individual units or pieces which fitted together make up the retort be such as to make each unit or piece capable of expansion and contraction without throwing any strain upon the neighboring units or pieces. We have also found that it is highly advantageous that each piece in the built-up retort be of such shape and size that it may be densely pressed, uniformly dried and burned, and be free of internal strain, which in effect calls for the use of the smallest pieces practicable. Moreover, since the retort is to be supported and tied into the furnace structure at only one place, the disposition of the retort in a vertical position becomes essential, and a cylindrical retort highly advantageous, because under such conditions the retort may be appropriately supported at its lower end with sufficient thickness of wall to carry the weight of the entire retort without bending or wobbling, and because a cylinder exhibits the least harmful effects of heating strains when it is repeatedly heated up and cooled down.

Our present invention accordingly contemplates the provision of an externally heated and vertically disposed reducing chamber for zinciferous material built up of a multiplicity of units or pieces of temperature-resistant material bonded together horizontally or vertically and horizontally into a substantially zinc-vapor-tight chamber supported and tied in at its lower end only. The individual temperature-resistant units or pieces are preferably annular, or cylindrical, or standard brick shapes such as circle, key, cupola, ring section or kiln.

These units or pieces are moreover of such shape as to permit independent expansion and contraction of each unit or piece without thereby imparting any objectionable strain to adjacent units or pieces. To this end, it is our preferred practice to provide substantially plain butt joints between adjacent units or pieces. To minimize expansion and contraction, it is desirable that the temperature-resistant units or pieces be made of temperature-resistant material having a relatively low temperature coefficient of expansion, and since the reducing chamber is externally heated, the temperature-resistant material should preferably have good heat conductivity. Silicon carbide or carborun-

dum, aluminum oxide, zirconium oxide and zirconium silicate are satisfactory materials for this purpose. The individual temperature-resistant pieces are extruded or machine-pressed under pressure to give high density and are dried and hardened (fired) under conditions adapted to minimize the strains remaining therein or likely to develop in the heating up of the chamber or retort they go to make up.

The principles of the invention and their practical application to the construction of reducing chambers for zinc smelting will be best understood from the following description taken in conjunction with the accompanying drawings in which

Fig. 1 is a sectional elevation of a zinc reducing or smelting furnace embodying the novel built-up reducing chamber of the invention,

Fig. 2 is a section of the furnace shown in Fig. 1 on the section line 2—2,

Fig. 3 is a combined sectional elevation and cross-section of a modified construction of built-up retort embodying the invention, and

Fig. 4 is a combined sectional elevation and cross-section of another modified form of the invention.

Referring to Figs. 1 and 2 of the drawings, the built-up retort 10, embodying the principles of the invention, is surrounded by a heating chamber or laboratory 11. The heating chamber 11 is built within a furnace structure comprising an outer steel shell or casing 12, a layer of Sil-o-cel powder 13, an intermediate lining 14 of one or more layers of fire brick or other appropriate material and an inner lining 15 of heat-refractory or temperature resistant material such, for example, as Carbofrax brick. Appropriate openings are provided through the wall of the furnace structure permitting the insertion of pyrometers 16 within the heating chamber 11 for ascertaining and appropriately controlling the temperature throughout the length of this chamber.

The furnace illustrated in the drawings is heated by the hot products of combustion from burning gas, although it is to be understood that any appropriate means may be employed for heating the reducing chamber or retort 10. The fuel gas is supplied from a gas main 17 to a plurality of vertical passages of conduits 18 arranged within a recuperator 19 built within the furnace structure alongside of the heating chamber 11. Similarly, air is supplied from a main 20 to a plurality of passages or conduits 21 in the recuperator. The passages 18 and 21 are provided in a plurality of spaced vertical walls 22 built up of temperature-resistant brick, tile or the like. It will be understood, of course, that the lining of the recuperator may be built of less temperature-resistant

material than the lining of the heating chamber 11, and that the recuperator will be provided with appropriate clean-out openings for the various gas passages thereof.

- 5 From the top of the recuperator the pre-heated fuel gas and air are delivered from their respective passages 18 and 21 to an appropriate mixer and burner (not specifically shown) near the top of the heating chamber
- 10 11. The resulting hot products of combustion pass downwardly around the retort 10 to an outlet 23 near the bottom of the heating chamber 11, and thence upwardly through a vertical flue 24 to the top of the
- 15 recuperator. The recuperator is provided with staggered horizontal baffles 25 which cause the heating gases to follow a zig-zag path in their flow through the recuperator to the gas outlet 26 and stack 27.
- 20 The furnace structure of the heating chamber 11 is mounted on a metal base plate 28 supported on an appropriate foundation 29 of concrete or the like. The base plate 28 supports the built-up retort 10 and has
- 25 a central opening directly beneath and of the same dimensions as the interior cross-section of the retort. A metal cylinder 30 is bolted, or otherwise appropriately secured, to the underside of the base plate 28
- 30 and serves as an extension of the retort 10 below the base-plate. A rotating table 31 is mounted directly beneath and appropriately spaced from the bottom of the cylinder 30 and serves to support the charge in
- 35 the retort 10 and, by its rotation in conjunction with a plow or scraper, permits the discharge of spent residues from the bottom of the retort as desired. From the rotating table 31 the spent residues are delivered to a conveyor or other appropriate means of removal not shown in the drawings.

The built-up retort 10 is supported exclusively at the base and is at no other place throughout its length attached to or otherwise tied into the heating chamber or furnace structure. The upper end of the retort extends freely through the top of the furnace structure. A cylindrical metal casting 32, preferably a nickel-chromium iron alloy such as Hybnickel, rests on top of the retort. A ring of ordinary fire brick 33 is preferably interposed between the top Carbofrax ring of the retort and the cylinder 32, in order to keep the Carbofrax brick from contact with the metal. The cylinder 32 is surrounded by a layer of hardened carbon paste 34 encased by sheet metal 35, which in turn is surrounded by a mass of dust coal 36 confined by a sheet metal wall 37. This dust coal also provides a mobile seal between the retort and the opening in the top of the furnace structure through which the retort extends. The metal cylinder 32

65 with its surrounding layer of hardened

carbon paste 34 thus rest on top of the retort 10 and are free to move therewith, and at the same time the top of the retort is effectively sealed. It will thus be seen that the retort 10 is supported entirely at its 70 base or bottom and is at no other place secured to or tied into the furnace structure, and is therefore free to expand or contract as it will.

The metal cylinder 32 has a lateral gas 75 outlet 38 lined with a graphite tube 39 leading to an appropriate condenser, preferably of the type described in the patent application of Frank G. Breyer, Serial No. 167,135, filed February 10, 1927, but not illustrated 80 in the accompanying drawings. The top of the cylinder 32 is provided with a charging device comprising an inverted sheet metal funnel 40 appropriately mounted within the cylinder and a movable plug or bell 41. 85 The space between the funnel 40 and the cylinder 32 is filled with darkened carbon paste 42 and an overlaying mass of dust coal 43, in which the rim or edge of a cover 44 is embedded.

Where the gas offtake (38-39) of the retort operatively enters or abuts on the condenser or any other appurtenance, which is relatively fixed with respect to the expanding or contracting movements of the retort, 90 it is important that the connection be adjustable to permit such relative movements. Or, if desired, this connection may be made and broken after the retort is up to heat and before it is cooled down, respectively. 95 The condenser or other appurtenance to which the gas offtake of the retort is operatively connected may be adjustable as to height, and then raised or lowered as the expanding or contracting retort wall raises 100 or lowers the gas offtake.

The retort 10 is built up of a multiplicity of superposed annular units 10' of appropriate temperature-resistant material. In the furnace illustrated in the drawings, the retort 10 is 40 feet long or tall and 2 feet internal diameter and has a wall thickness of 4½ inches. The dimensions of each annular element or unit 10' are 24 inches inside diameter, 33 inches outside diameter, 4½ inches wall thickness and 2½ inches high.

The annular units 10' are preferably made of silicon carbide (or carborundum) grain accurately sized and preferably shaped by extrusion under pressure to give the maximum density. The annular units are given two firings, the second at a higher temperature than the units are expected to attain in use, with the idea of relieving all strains and bringing out any faults, so that imperfect 110 units may be discarded.

The retort 10 is built up from the base by laying these annular units one upon another. The joints between the superposed units are filled with Carbofrax cement and the units 115

are pressed or hammered down into place with joints of preferably one-eighth inch or less. As the joint filler or cement we preferably use Carbofrax No. 4 cement, consisting 5 principally of sized carborundum and a small amount of glutrim binder or dried sulfite liquor and a small amount of clay. By the addition of water, the cement is made just plastic enough to flow under pressure, 10 but is made sufficiently dense to leave a real body of carborundum in the joint when the water of the cement evaporates. The retort 10 may in this manner be built up to great heights provided it is not tied in with any 15 furnace wall or kicker which would interfere with its free and uniform expansion as it heats up. The low temperature coefficient of expansion of Carbofrax brick is of particular advantage in constructing such large 20 retorts.

The retort 10^A illustrated in Fig. 3 is built up in substantially the same manner as the retort 10 of Figs. 1 and 2. The individual pieces 10^A' with which the retort 10^A is built 25 up, while annular units, are perhaps more aptly described as cylindrical elements or units. The dimensions of the retort itself are substantially the same as the retort 10, and the cylindrical units 10^A' are 6 inches 30 in height and have a wall thickness of approximately 3 inches.

Where the retort is built up of integral cylindrical or annular units, as distinguished from units assembled from brick or small 35 shapes, we prefer that the height or vertical dimension of these units should not exceed about 6 inches, in order that the advantages of our improved built-up construction may be realized to the fullest degree. On the 40 other hand, we have successfully operated for many months a cylindrical vertical retort 25 feet in height and built up in accordance with our invention of cylindrical units 18 inches in height.

The retort 10^B illustrated in Fig. 4 is built 45 up of brick 10^B'' preliminarily assembled in the annular units 10^B'. The brick 10^B'' are Carbofrax circle brick of the following approximate dimensions: 9 inches by 6¹/₈ 50 inches by 4¹/₂ inches by 2¹/₂ inches. Twelve of these circle brick are used in making up each annular unit 10^B'. The dimensions of 55 the annular units are: 24 inches inside diameter, 33 inches outside diameter, 4¹/₂ inches wall thickness and 2¹/₂ inches high.

The circle brick 10^B'' are preferably made of silicon carbide, or carborundum, grain accurately sized and further machine-pressed to give the maximum density. The 60 brick are given two firings for the reasons hereinbefore mentioned. Such brick run remarkably true to shape and size after the double firing. Nevertheless, it is our preferred practice to treat these brick on a revolving sand grinding table where all ir- 65

regularities are eliminated, the contacting surfaces of the brick cut smooth and any faults covered over by the surface glaze revealed and the faulty brick rejected.

After the smoothing and uniforming 70 operation on the revolving sand table, the brick are sorted to sizes within one-sixty-fourth ($\frac{1}{64}$) of an inch on the vertical or 2¹/₂ inch dimension. Twelve of these circle brick are then laid in a ring upon a plane 75 surface and the vertical joints filled in with Carbofrax No. 4 cement. By the addition of water, the cement is made just plastic enough to flow under pressure, but is made 80 sufficiently dense to leave a real body of carborundum in the joint when the water of the cement evaporates. The vertical joints between adjacent brick in the ring are made up with an initial thickness of $\frac{1}{8}$ inch or more of cement. Two or three heavy iron 85 wires are next placed around the assembled ring of circle brick and the ends of the wires twisted together so as to exert a very powerful contracting and compressing force. Under such treatment the vertical joint between adjacent brick is reduced to $\frac{1}{16}$ inch or less.

The retort 10^B is now built up from the base by laying these rings of circle brick one upon another. In this operation the 90 rings are handled as units, the brick in each ring or unit being tightly held together by the encircling wires. The horizontal joints between the superposed rings are filled with 95 Carbofrax cement and the rings are hammered down into place with joints of $\frac{1}{8}$ inch or less. The horizontal joints between the superposed rings, being at all times under compression in consequence of the weight of the superposed rings, need not be so carefully 100 made as the vertical joints between individual circle brick in each ring, which latter joints are under less compressive strain after the encircling wires are removed. The encircling wires are removed when some four or 105 five feet of the retort structure has been built thereabove, the weight of the superposed structure being then sufficient to keep the lower individual circle brick in position. In 110 this manner, the retort 10^B may be built up to great heights, provided it is not tied in with any furnace wall or kicker which would interfere with its free and uniform expansion as it heats up.

While in our preferred practice the filling 115 material, cement or bond in the joints between the annular or cylindrical units or the individual brick or pieces may harden and solidify when cold so as to be a true bond between the pieces, stronger in some cases than the pieces themselves, this condition of the cold strength of the filling material is not essential. The function of the filling material in the joints is to furnish a filler for the 120 cracks which would otherwise be present, 125

and to make the joints sufficiently dense to be substantially non-porous to zinc vapor. The filler in the joints must moreover have the capacity of not fusing away at the elevated temperatures to which the reducing chamber is subjected, but must stay in position in the joints. It is for these reasons, among others, that we particularly specify that the filling or bonding material be made up with as high a percentage of solids and as small a percentage of water or other slip promoting material as possible. This preference for a dense filling material makes thin uniform joints more difficult of attainment, particularly in the vertical joints, but our improved method of assembling the pieces overcomes this handicap and makes possible zinc-vapor-tight joints. When, therefore, we speak of the pieces being "bonded" together we mean that the joints, both horizontal and vertical, are so filled as to be substantially zinc-vapor-tight under operating conditions.

It is to be understood that the reducing chamber may be of any desired sectional configuration. While we have herein spoken of the units 10', 10^A and 10^B as "cylindrical" or "annular" in shape, we have used these words without restriction as to the exact configuration of the units. In general, we prefer these units to be of circular section, but it is to be understood that the units may be elliptical, oval or of any other appropriate sectional configuration.

It has heretofore been considered desirable to construct built-up muffles or retorts with a minimum number of joints. As a result of our investigations and experiments we have found that this does not hold for a built-up vertical zinc retort. Thus, we have found that the number of joints in a built-up vertical zinc retort may with advantage be increased to the number required by standard machine-pressed brick shapes, more particularly where, as in our present invention, the reducing chamber or retort is supported only at its base and not otherwise tied into the furnace structure.

As hereinbefore stated, we have found that the individual units or pieces which fitted together make up the retort be of such shape as to make each unit or piece capable of expansion and contraction without throwing any strain upon the neighboring units or pieces.

In our early experiments, we built up the vertical retort with Carbofrax cylindrical units or sections having bell and spigot joints such as commonly used for joining pipe lengths of various kinds. These sections were 18 inches long or high, 15 inches internal diameter with a wall thickness of about 2 inches. In the operation of this built-up retort, the bell and spigot joint not only proved of no advantage but a positive and

very serious disadvantage; and this in spite of the fact that Carbofrax ware is unusually strong for non-metallic temperature-resistant material, and moreover has a very low temperature coefficient of expansion. This retort failed by the cracking and falling out of a big piece of the retort wall as a consequence of putting cold charge into the upper end of the retort when the latter was at a temperature around 1200° C. When the assembly was inspected after cooling down, a number of cracks were found in the retort in addition to the several which were the direct and principal cause of the failure. In every case, these cracks started or ran away from either the bell or spigot ends and generally extended from one spigot end into the bell end of the next lower unit or section. The evidence was unmistakably clear that the sections were unusually liable to start cracking from the bell end and that if a crack ran down a section to the spigot end it was almost certain to crack the bell of the unit below, because of the confinement of the spigot within the bell of the next lower unit.

It required considerable courage on our part to take off the bell end of the units thereby leaving them true sections of cylinders with no tie-in from one section to another, other than the plastic bond between the joints. The units or sections were then of the form illustrated in Figs. 1, 2 and 3 of the accompanying drawings. Such units can not only be made and burned with considerably less strains remaining in them, but, assembled and in operation can expand irregularly with respect to one another. That is to say, if one unit in the heating up tends to expand elliptically or egg-wise on one axis and another unit tends to do the same thing on another axis, they may do so without one unit throwing a strain upon another unit. Under these circumstances, the flow or movement takes place in the plastic cement or joint filler. These true cylindrical or annular units gave very superior service to that obtained with the bell and spigot units.

Pursuing the same line of reasoning, but assuming that even the best of such sections or units may crack, the question of keeping the cracked piece from falling out and absolutely ruining the entire retort leads to the following conclusions which we have checked by actual field experiments.

The lower the vertical height of such cylindrical pieces and the thicker the walls, the less chance there is of a cracked piece falling out. Take the case where the annular units are say 4½" thick and only 2½" high. If such an annular unit develops two cracks from the top to the bottom, that is, through the 2½" dimension, the loose piece would not fall out even if there were no

cement bond in the joints because the loose piece is held as a flat layer with a $4\frac{1}{2}$ " of bearing surface on its upper and lower sides.

It is accordingly our preferred practice to 5 go to rings or assembled rings made up of circle brick or other standard ring-forming shapes which are of relatively low vertical height and preferably of less vertical height than the ring width or wall thickness. In 10 making a temperature-resistant ring from a plastic base, it is always possible to make and burn a flat ring better than a square one or one of greater height as compared with its wall thickness.

15 As a last precaution to insure as good a built-up retort as possible, from the stand-point of absence of residual strain which might later develop cracks in operation, these annular units may be heated up and 20 very suddenly cooled to make the residual strains crack the unit exactly as they would in operation. The cracked unit which has a material tendency to open outward may then 25 have the thin cracks filled with cement which when burned with the unit in final position constitutes a zinc-vapor-tight joint. Or, if desired, the annular units may be mechanically broken instead of cracked by heat strains, and the cracks filled with cement. 30 The last step in this direction is to construct the built-up retort of annular units that are themselves built up of circle brick or the like as illustrated in Fig. 4 of the drawings.

35 The advantages of the built-up vertical reducing chamber of the invention are many. The fact that the reducing chamber is supported at its base only and not otherwise tied into the furnace structure makes possible a 40 relatively large and long-lived chamber capable, more especially when the individual units are made of carborundum, of being heated to very high temperatures and of being shut down and started up again without 45 being damaged by cracks or other faults. The use of but one simple shape for the building up of the entire chamber makes for simplicity and cheapness of construction. With such simple shapes maximum density 50 of the temperature-resistant material may be obtained, thereby giving good heat conductivity. When the built-up retort or chamber of the invention with its multiplicity of joints is heated up small strains, which are 55 bound to occur, and differences in expansion in different parts of the structure, due to slightly nonuniform heating, or to slight differences in the density of the materials, may be relieved by flow in the cement or filler in 60 the joints, thereby avoiding cracks in the chamber as a whole, which are hardest to avoid in the heating up period of any temperature-resistant structure. Even after the 65 structure has reached high temperatures and the bond in the joints has set, it is probable

that flow can take place in the bond more readily than it could take place in a true monolithic structure, and consequently strains will still be relieved at high temperatures.

70 While it is our preferred practice to use the simplest forms of annular, cylindrical or standard brick shapes with plain butt joints, it may under certain circumstances be desirable to make a small departure from this practice by providing the units or shapes with tongue and groove or equivalent joints. With such joints, it is important that the grooves be not too deep and that good clearance be provided therein for the tongues. It 75 should be borne in mind, however, that all such complications of shape tend to take away from the solidarity, trueness to shape and size, and the freedom from strain and cracks of the individual pieces. They, moreover, tend to restrict the flow in the bond, which is necessary where one piece must move with respect to another, in order to relieve strains in the assembled structure. We 80 have found it entirely satisfactory to use 85 nothing but plain butt joints.

We claim:

1. An externally heated vertical reducing chamber for the reduction of zinciferous material supported and tied in at its lower end only and built up of a multiplicity of pieces 95 of temperature-resistant material assembled into a substantially zinc-vapor-tight chamber.

2. An externally heated vertical reducing chamber for the reduction of zinciferous material supported and tied in at its lower end only and built up of a multiplicity of pieces 100 of temperature-resistant material fitted together with plain butt joints into a substantially zinc-vapor-tight chamber.

3. An externally heated vertical reducing chamber for the reduction of zinciferous material supported and tied in at its lower end only and built up of a multiplicity of pieces 105 of temperature-resistant material fitted together with plain butt joints filled with a material that makes the chamber as a whole substantially zinc-vapor-tight.

4. An externally heated vertical reducing chamber for the reduction of zinciferous material supported and tied in at its lower end only and built up of a multiplicity of superposed annular units of temperature-resistant material assembled into a substantially zinc-vapor-tight chamber.

5. An externally heated vertical reducing chamber for the reduction of zinciferous material supported and tied in at its lower end only and built up of a multiplicity of superposed annular units integrally made up of temperature-resistant material, said units being fitted together with plain butt joints into a substantially zinc-vapor-tight chamber.

6. An externally heated vertical reducing 130

- chamber for the reduction of zinciferous material supported and tied in at its lower end only and built up of a multiplicity of superposed annular units of temperature-resistant material assembled with plain butt joints into a substantially zinc-vapor-tight chamber.
7. An externally heated vertical reducing chamber for the reduction of zinciferous material supported and tied in at its lower end only and built up of a multiplicity of pieces of temperature-resistant material jointed both horizontally and vertically into a substantially zinc-vapor-tight chamber.
13. The method of making a built-up vertical retort for the reduction of zinciferous material which comprises assembling a plurality of substantially standard brick shapes into an annular unit with filled vertical joints, reducing and compressing the vertical joints between the individual brick shapes by encircling and holding compressing means, and laying said assembled annular units one upon another with filled horizontal joints while maintaining the encircling and holding compressing means for each unit until the weight of the superposed structure is sufficient to hold the individual brick shapes in position.
14. The method of making a built-up vertical retort for the reduction of zinciferous material which comprises assembling a plurality of pieces of temperature-resistant material into an annular unit with filled vertical joints, reducing and compressing the vertical joints between the individual pieces, and superposing a multiplicity of said assembled annular units with filled horizontal joints while maintaining the vertical joints of each unit under compression.
15. The method of making a built-up vertical retort for the reduction of zinciferous material which comprises assembling a plurality of circle brick into an annular unit with filled vertical joints, reducing and compressing the vertical joints between the individual brick, and laying said assembled annular units one upon another with filled horizontal joints while maintaining the vertical joints of each unit under compression.
16. The method of making a built-up vertical retort for the reduction of zinciferous material which comprises assembling a plurality of circle brick into an annular unit with filled vertical joints, reducing and compressing the vertical joints between the individual brick by encircling and holding compressing means, and laying said assembled annular units one upon another with filled horizontal joints while maintaining the encircling and holding compressing means for each unit until the weight of the superposed structure is sufficient to hold the individual brick in position.
- In testimony whereof we affix our signatures.
- FRANK G. BREYER.
